UNITED STATES PATENT OFFICE.

HENRY P. STICHTER, OF POTTSVILLE, PENNSYLVANIA.

BLACKING-BOX.

SPECIFICATION forming part of Letters Patent No. 244,334, dated July 12, 1881.

Application filed November 30, 1880. (No model.)

To all whom it may concern:

Be it known that I, HENRY P. STICHTER, of Pottsville, Pennsylvania, have invented a new and useful Blacking-Box, of which the following is a specification.

My invention relates to boxes for holding boot and shoe blacking, and the object of it is to provide a box having rounded or partly-rounded bottom, and provided with a suitable tablet for distributing and mixing the blacking.

In the accompanying drawings, Figures 1 and 2 are plan views of my invention, and Figs. 3 and 4 are sectional views of the same.

15 A is the receptacle for the blacking, and B is the distributing or mixing tablet.

In Figs. 1 and 3 is shown a box having a completely-rounded bottom, while in Figs. 2 and 4 the bottom is shown only partially rounded. The object of this form of construction in the bottoms is to prevent the waste of blacking, which is considerable in ordinary boxes having flat bottoms.

25 In the ordinary boxes a great part of the blacking is not used, owing to the trouble and difficulty of getting at the corners of the box with a blacking-brush. In my box there are

no corners, and every particle of the blacking can be used.

The tablet in connection with the box is used 30 for mixing and distributing the blacking evenly and thoroughly on the brush.

The box and tablet may be struck up with dies out of a single piece of metal. I encircle the box and tablet with a rim, C, and provide 35 a lid, (not shown in the drawings,) which may either cover the whole device or the blacking-receptacle alone.

My invention forms a neat, cleanly, and convenient blacking-box, enabling the user there- 40 of to use up all the blacking in the receptacle without inconvenience or trouble, and providing the tablet for evenly distributing the blacking on the brush.

What I claim is—
45 The combination, in a blacking-box, of the blacking-receptacle A and distributing-tablet B, together with the strengthening rim or band C, substantially as shown and set forth.

HENRY P. STICHTER.
